UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

Application filed August 1, 1928. Serial No. 296,651.

This invention relates to locks, and particularly to a type of lock operated in a manner to operate a latch with one key, and in a manner to operate a locking bolt 5 with a special or master-key.

An object of the invention is to provide a lock adapted for normal use by the insertion of an ordinary key, but which, by the use of a special master-key, may be operated in a different or modified manner.

A further object of the invention is to provide a lock of the tumbler type, the key receiving part of which is adapted to be oscillated between fixed limits by the use 15 of an ordinary key, but which is adapted to be freely rotated by the insertion of the special or master-key.

Another object of the invention is to provide interengaging abutments on a portion 20 of the lock and on a part movable with the key plug and adapted normally to be engaged upon oscillation of the key-receiving plug, the abutment on the roll-back being movable upon insertion of a special key to 25 avoid engagement with said projections.

Another object of the invention is to provide a member movable along the roll-back of a lock toward and from its axis of rotation, this slide being normally spring 30 pressed in one direction and having a projection which, in one position, will engage and limit oscillation of the plug by contacting with fixed projections on the cylinder, but when moved against the spring, the 35 projection on the roll-back avoids engagement with said outstanding projections on the cylinder and the plug is free to rotate.

A further object of the invention is to provide a special key, insertible in the key-receiving plug and being fitted to control the tumblers in the usual manner and providing means adapted to engage and actuate a slide movable on the roll-back.

With these and other objects in view, my 45 invention consists in the features of construction and operation set forth in the following specification and illustrated in the accompanying drawing.

In the accompanying drawing annexed 50 hereto and forming a part of this specification, I have shown my invention embodied in a multiple tumbler lock, but it will be understood that the invention can be otherwise embodied and that the drawing is not

to be construed as defining or limiting the 55 scope of the invention, the claims appended to this specification being relied upon for that purpose.

In the drawing—

Fig. 1 is a rear elevation of a lock provided with the present invention;

Fig. 2 is a similar view of the lock, but with certain parts moved to a different position;

Fig. 3 is a view taken upon the line 4—4, 65 with the parts of the roll-back in the position shown in Fig. 1;

Fig. 4 is a view taken upon the plane of the line 4—4, with the parts of the roll-back moved to the position shown in Fig. 5; and 70

Fig. 5 is a side elevation of a complete lock, the roll-back being shown in section to more clearly show the movable parts thereon.

In the above mentioned drawing I have 75 shown but one embodiment of the invention, which is now deemed preferable, but it is to be understood that changes and modifications may be made within the scope of the appended claims, without departing 80 from the spirit of the invention.

Referring more in detail to the figures of the drawing, I show a lock cylinder 10 of the conventional or standard multiple tumbler type, having a key-receiving plug 85 11 rotatably mounted therein and tumblers (not shown) operating within the cylinder 10 adapted to enter holes in the plug. As these parts may be of any well known form, it is not thought necessary that they be 90 further illustrated. It will be understood that when a key 12 of the general form shown in outline in Fig. 5 is inserted within the plug 11, the plug 11 will move the tumblers to a position permitting oscillation of 95 the plug 11 together with the roll-back 13 attached to its rear face.

Outwardly projecting from the rear face of the cylinder 10 are pins 14 or other forms of projections, fixed rigidly in position and 100 limiting the oscillatory movement of the plug 11 by contacting with a part 15 on the roll-back 13. The part 15 on the roll-back 13 engaged by the pins 14 comprises a small 105 forwardly extending projection attached permanently in any preferred manner to a slide 16 movable within ways extending longitudinally along the roll-back 13. With

the projection 15 and slide 16 in the position shown in Figs. 1 and 3, a portion of the projection 15, when the plug 11 is oscillated, strikes the pins 14, and therefore 5 limits oscillatory movement of the roll-back 13. This movement, however, is sufficient for normally operating the latch of the lock, which is accomplished by a key of the conventional type accommodated to the 10 tumblers used in the lock.

In order to freely rotate the plug 11 and roll-back 13 throughout a complete revolution, means is provided for moving the projection 15 and the slide 16 carried by the 15 roll-back 13 to a position where it will not contact with the pins 14 when the plug 11 is oscillated. This is accomplished by the insertion of a special key 12 of greater length than the ordinary key, the mid-section 20 of which is fitted in accordance with the tumbler system of the lock, and the rear end has a projection 17 striking and forcing outwardly the slide 16 movable within the roll-back 13. Movement of the slide 16 to the 25 position shown in Figs. 2, 4 and 5 moves the projection 15 carried by the roll-back 13 to a position beyond that in which it would engage the pins 14. The roll-back 13 is suitably recessed as shown at 18 in those 30 portions which would otherwise come in contact with the outstanding pins 14. With the slide 16 forced to its outer position, the roll-back 13 is enabled to pass over the pins 14 and be freely rotated with the plug 11. This 35 complete rotative movement of the plug 11 and roll-back 13 may be used to operate the locking bolt of the lock.

I claim:

1. In a lock, a cylinder, a rotatable key-receiving plug therein, a rollback on said plug, and abutment means on said cylinder and rollback for allowing a limited rotation of said plug, said abutment means being relatively movable to avoid relative engagement thereof, for the purpose described. 45

2. In a lock, a cylinder, a rotatable key-receiving plug therein, a rollback on said plug, and abutment means on said cylinder and rollback for allowing a limited rotation of said plug, said abutment means being relatively movable by a key insertible in said plug to cause said abutment means on said rollback and cylinder to avoid engagement, for the purpose described. 50

3. A lock comprising, in combination, a cylinder, a rotatable key-receiving plug therein, a rollback secured to said plug, projections on said cylinder, a slide on said rollback engaged by said projections whereby the rotative movement of said rollback is limited, and means to move the slide on said rollback to avoid engagement with said projections. 55

4. A lock comprising, in combination, a cylinder, a rotatable key-receiving plug therein, a rollback secured to said plug, projections on said cylinder, a slide on said rollback having a projection thereon engaged by said projections when said slide is in one position whereby the rotative movement of said rollback is limited, and means to move the slide radially outward on said rollback to avoid engagement with said projections. 65

5. A lock comprising, in combination, a cylinder, a rotatable key-receiving plug therein, tumblers movable between said cylinder and plug, a rollback secured to said plug, a slide movable along said rollback, a projection on said slide extending closely adjacent the end of said cylinder, fixed projections outstanding from the end face of said cylinder normally engaged by said projection on said slide and limiting rotation of said plug, and means insertible in said plug for moving said slide and its projection to avoid engagement with said projections on said cylinder. 70 80 85
